UNITED STATES PATENT OFFICE.

WILLIAM H. WAHL, OF DES MOINES, IOWA.

RADIATOR STRUCTURE FOR FURNACES.

Application filed October 16, 1922. Serial No. 594,757.

To all whom it may concern:

Be it known that I, WILLIAM H. WAHL, a citizen of the United States, and a resident of Des Moines, in the county of Polk and 5 State of Iowa, have invented a certain new and useful Radiator Structure for Furnaces, of which the following is a specification.

It is the object of my invention to provide a radiator structure for furnaces, which 10 is of simple and inexpensive construction.

More particularly, it is the purpose of my invention to provide such a radiator, which can be very readily and easily adapted for use on a great many different makes of furnaces to make it possible to utilize a maximum of the heat generated by combustion.

A further purpose is to provide such a radiator which is especially adapted for use in connection with steam or hot water furnaces and boilers, whereby there may be secured a maximum utilization of the heat generated, and whereby heat that might otherwise be wasted may be used for warming air for heating rooms or buildings.

25 A further purpose is to provide such a radiator structure of peculiar make-up for securing maximum efficiency and also accurate control of the heat and drafts.

With these and other objects in view, my 30 invention consists in the construction, arrangement and combination of the various parts of my device, whereby the objects contemplated are attained, as hereinafter more fully set forth, pointed out in my claim, and 35 illustrated in the accompanying drawings, in which:

Figure 1 shows a perspective view, partly in section, with parts broken away of a furnace equipped with a radiator structure embodying my invention.

Figure 2 shows a vertical sectional view through a portion of the radiator structure and the top of a furnace; and

Figure 3 shows a similar view illustrating 45 the method of mounting a radiator structure of standard size on a furnace, having a small smoke outlet.

In the accompanying drawings, in which I have illustrated the way in which my 50 radiator structure may be embodied, I have used the reference numeral 10 to indicate generally a hot water boiler and furnace, equipped with a radiator structure embodying my invention.

55 The top 11 of the furnace has an opening 12, which forms the outlet through which

the smoke and products of combustion ordinarily pass to the chimney or stack.

My radiator structure comprises an elongated tubular member 13, the ends of which 60 are preferably round, as at 14 and 15. The end 15 is designed to be connected with a pipe leading to the chimney or stack, while the end 14 is designed to be closed by a clean-out cover 16, which may be mounted 65 on the member 13 or on a casing 17, which encloses the furnace and boiler 10 and has its side walls spaced from the furnace and boiler 10.

For convenience, I have called the end 15, 70 the rear end of the member 13 of the radiator.

Communicating with the tubular member 13 of the radiator at its sides near its forward end are conducting pipes 17^a, which 75 are arranged to extend around the sides of the furnace and boiler 10, substantially as shown in Figure 1, toward the back of the furnace, and are inclined downwardly from their forward to their rear ends, as shown.

80 The lower ends of the conducting pipes 17^a communicate with a curved hollow drum 18 extending around the back of the furnace between the rear ends of the conducting pipes 17^a.

85 At each end of the drum 18 is a clean-out passage 18^a at the end of which is a door 18^b.

The two sides of the device are of similar construction.

90 A connecting pipe 19 communicates with the drum 18 near the middle thereof from end to end at the top of said drum and extends upwardly and communicates with the lower side of the tubular member 13 near the rear end thereof as shown in Figure 2.

95 Between the ends of the tubular member 13, said member is provided with an enlarged portion 20 designed to be connected with the flange 21 around the opening 12 for affording means of communication between the top of the furnace 10 and the radiator member 13.

In the pipe 19, there is mounted an ordinary damper 22 of the throttle valve type on a stem 23, which projects out of the 105 pipe 19.

110 In the radiator member 13 between the member 20 and the pipe 19 is mounted a damper 24 of the throttle valve type, having a stem 25, which projects from the tubular radiator member 13.

On the stem 23 is an arm 26 and on the

stem 25 is an arm 27. A link 28 is pivoted at its ends to the respective arms 26 and 27, as shown in Figure 1.

The dampers and their arms and the connecting link 28 are so arranged, as illustrated for instance in Figure 1, that the damper 22 is open when the damper 24 is closed, and so that when the dampers are manipulated for opening the damper 24, such manipulation will serve to close the damper 22.

A controlling rod 29 is connected preferably with the arm 27 and extends forwardly through a suitable guide 30 to a convenient point of access in front of the furnace.

The casing 17 is provided with suitable doors 31 closing passages 32 leading to the combustion chamber of the furnace.

The casing is also provided with an ash cleanout door 33 closing the passage 34 leading to the ash pit.

A draft door 35 is preferably mounted on the door 33 and hinged at its upper edge.

For permitting simultaneous control of the dampers 22 and 24 and the draft door 35 by means of the operation of the control rod 29, I have provided the following means:

On the rod 29 is fixed a collar 36. A bell crank lever device 37 has one arm pivoted, as at 38, on some fixed part of the structure and has pairs of upwardly projecting fingers 39. Each pair of fingers receives between its members the rod 29, as shown in Figure 1, and the pairs of fingers are located on opposite sides of the collar 36, so that when the rod 29 is moved longitudinally, the bell crank lever structure 37 will be swung on its pivot 38.

Another arm of the bell crank lever 37 is pivoted at 40 to a link 41, which extends downwardly. Near the lower end of the link 41, a bell crank lever 42 is pivotally mounted at 43 on the bracket 44 or other fixed part of the structure.

One arm of the bell crank lever 42 is pivoted to the lower end of the link 41. The other arm of the bell crank lever 42 has a pin 45 projected through an elongated slot 46 in a controlling arm 47, which is fixed to the lower part of the draft door 35, as for instance by means of a rigid rod 48.

Where my device is used with a hot water furnace for instance, the hot water pipes 49 extend through the wall of the casing 17, for instance as shown in Figure 1.

I will now explain the practical operation of my improved radiator structure briefly and will then refer to some of its advantages.

It will be seen that the smoke and products of combustion from the furnace 10 pass upwardly through the opening 12 into the tubular member 13 of the radiator structure. If the damper 24 is then open, the damper 22 will be closed, and the products of combustion pass directly to the stack or chimney,

which permits the securing of a strong draft for starting a fire.

After combustion is well under way, the dampers are moved to the positions shown in Figures 1 and 2, whereupon the products of combustion will pass into the member 13 and then forwardly therein to the conducting pipes 17^a. The smoke and products of combustion will then divide and pass rearwardly and downwardly through the pipes 17^a to the drum 18. In the drum 18, such products of combustion pass from the ends of the drum through the lower end of the pipe 19 and thence upwardly through the pipe 19 and the rear portion of the tubular member 13 to the chimney or stack.

When it is desired to increase the draft, the rod 29 is pulled forwardly.

When the particular construction shown in the drawings is employed, this movement of the rod 29 will serve to open the damper 24 and close the damper 22. At the same time, the bell crank lever 37 will be manipulated for shoving the link 41 downwardly and thus manipulating the bell crank lever 42 for shoving the arm 47 forwardly and opening the draft door 35.

When my radiator structure is used in connection with a hot water furnace and boiler for instance, I have secured a number of advantages.

Ordinarily, it is the custom to cover the boiler structure 10 with asbestos or provide other means for retaining the heat and preventing its radiation.

Where my structure is used, I do not use such an asbestos covering but use the casing 17 for leaving a space between the walls of the casing 17 and the furnace or boiler 10. There is thus left a wall of air around the furnace or boiler 10. Cold air is supplied to this space through the cold air duct 50. This air is warmed by heat radiated from the boiler and furnace and especially by heat radiated from my radiator structure members 17, 13, 18 and 19. There is thus always a cushion of warm air around the hot water boiler.

Any heat lost in the hot water boiler is transmitted to the air around.

Much of the heat of the products of combustion, which would otherwise pass out through the stack or chimney and be wasted, is utilized by means of radiation from the members 13, 17, 18 and 19.

The air thus heated by my device may be conducted through an ordinary pipe 51 to a room or building for heating in the ordinary way by hot air.

I find that with my structure I can heat practically as much water as can be done with the same hot water boiler without my device, while in addition, I can heat enough air to warm several rooms or a building.

Thus where a device of this kind is used

for three cottages arranged close together, it can be placed under one of the cottages, which can be heated by hot air, while the hot water can be conducted to the other cottages for heating them.

The device can be readily used with steam heating plants, and I find that it improves the results, even where used with an ordinary hot air furnace, since there is less loss by radiation from the furnace and by heat passing into the chimney, where my structure is used, than where devices now ordinarily in use, with which I am familiar, are employed.

My radiator structures are made in standard sizes and can be readily assembled in connection with furnaces of different sizes and makes, providing such furnaces have their smoke outlets at the top.

The member 20 is of a size to fit the larger openings 12 in furnaces, and where it is too large to fit the opening in the furnace, to which it is to be applied, I use a step-down connection sleeve 52, which is smaller at one end than at the other, as illustrated in Figure 3 for connecting the member 20 and the flange 21.

It will be understood that considerable changes may be made in the construction and arrangement of the details of my device without departing from the real spirit and purpose of my invention, and it is my intention to cover by my claim, any such

changes or modifications as may come within its scope.

For instance, the controlling means for the dampers and draft door may be varied in a great many ways as to details and yet the same general purpose can be readily accomplished.

I intend to cover the particular structure and arrangement shown, but I believe my invention is considerably broader than such arrangement and construction, and it is my purpose to cover all of my real invention.

I claim as my invention:

In a device of the class described, the combination of a furnace combustion chamber with a hot-air chamber having its walls spaced therefrom to leave an intervening compartment, a smoke conducting and radiator structure in said compartment, comprising a pipe extending across the top of the device having an enlarged portion communicating with the combustion chamber, pipes communicating with said first pipe at the forward portion thereof and extending downwardly and rearwardly, a curved hollow drum connecting the lower end of the last-described pipes, a pipe connecting the central portion of said drum with the rear portion of said first pipe, and a cold air duct communicating with said compartment below said drum.

WILLIAM H. WAHL.
